UNITED STATES PATENT OFFICE.

CHARLES R. CARLETON, OF BROOKLYN, NEW YORK.

PERFORATING MACHINE.

1,416,168.

Specification of Letters Patent. Patented May 16, 1922.

Application filed July 20, 1920. Serial No. 397,593.

To all whom it may concern:

Be it known that I, CHARLES R. CARLETON, citizen of the United States, and resident of Brooklyn, in the county of Kings and State 5 of New York, have invented certain new and useful Improvements in Perforating Machines, of which the following is a specification.

This invention relates to a machine for 10 perforating motion picture films, having more particular reference to a perforating machine in which the feeding, perforating and rewinding of the film are all mechanically accomplished.

15 The invention has for general objects to minimize or eliminate the chance of the oil used in lubricating the machine getting on the film; to render the operating mechanism easily accessible for replacement or otherwise, and to provide a machine of generally simple, compact, and durable construction.

For further comprehension of the invention, and of the objects and advantages thereof, reference will be had to the following description and accompanying drawings, and to the appended claims in which the various novel features of the invention are more particularly set forth.

Fig. 1 of the drawings is a front elevation of a perforating machine constructed according to the invention.

Fig. 2 is an enlarged partial transverse section on the line 2—2 of Fig. 1.

Fig. 3 is a detail longitudinal section on the line 3—3 of Fig. 2.

Fig. 4 is a horizontal section on the line 4—4 of Fig. 3.

Fig. 5 is a transverse section on the line 5—5 of Fig. 3.

40 Fig. 6 is a transverse section on the line 6—6 of Fig. 3.

Fig. 7 is a fragmentary axial vertical section of the film roll supporting device on the feed side of the machine.

45 Fig. 8 is a detail longitudinal section on the line 8—8 of Fig. 2.

Fig. 9 is a detail sectional view illustrating the construction of the main drive shaft, the section being transverse to the machine but longitudinal to the shaft.

Fig. 10 is a detail plan view of the die and the means for guiding the film across the same.

55 Fig. 11 is a fragmentary longitudinal section taken on the line 11—11 of Fig. 5.

Fig. 12 is a detail front view of the punch with the face plate removed.

As here embodied the perforating machine comprises briefly a punch head carrying a series of punch elements for perforating the film, and pilot elements for ensuring exact positioning thereof; a stripper for removing the film from the punches and pilots, a step by step shifter for advancing the film to the punches, and film feeding and re-winding devices.

As here shown the operating mechanism for the above devices is supported by and partially enclosed within, a casing 1 which is bolted on top of a suction box 2, the latter being supported on legs 3. Upon the top of this casing, midway between opposite ends thereof, is supported a die 4 which is adjustably secured to the casing by cap screws 5 passing through slots 6 in extensions 7 formed on opposite sides of the die. The die is formed with two rows of perforations 8 spaced as required for perforating the film. An opening 1' is formed in the top of the casing 1 under the die 4, a conduit 1^a extending from this opening toward one end of the casing and having a pipe 9 leading downwardly therefrom to the suction box 2 for the purpose of removing the punchings.

85 Co-operating with this die is a punch which here comprises a ram element 10 which extends downwardly at the rear of the casing 1 and has an integral forwardly projecting head 11 which overhangs the die 90 4, further reference to the parts carried by this head, being presently made. The ram 10 is guided in a suitable recess 12 in the back of the casing 1 and is held against displacement by a plate 13 bolted or otherwise secured to the casing, this plate having an offset 13' forming a support for the rear end of the main shaft of the machine.

95 Upon the main shaft of the machine, to which further detail reference will be made, is fixed a spiral pinion 15 meshing with a spiral gear 16 on another shaft 17 which extends longitudinally of the casing 1 and serves to operate the film feeding and re-winding devices. The opposite ends of this 100 shaft extend through and are journaled in hollow arms 18, (Fig. 8) bolted on opposite sides of the casing 1, and have each fixed thereon a spiral gear 19 which meshes with a like gear 20 on the lower end of a shaft 110

21 extending upwardly in a standard 22 supported on the arm 18. Each shaft 21 has a bevel gear 23 on its upper end which meshes with a like gear 24 on a horizontal stub shaft 25, these shafts 25 being supported in the standards 22 and having film advancing rollers 26 and 27 respectively on their outer ends, (Fig. 1), the roller 25 which is on the feeding side of the machine having a smooth periphery while the roller 27 on the re-winding or take-up side of the machine is toothed. Co-operating with the rollers 26 and 27 are usual film guiding rollers 28, while a suction cleaning device 29 of ordinary construction through which the film passes is located immediately below the roller 27, this suction device being connected by a pipe 30 with a coupling member 31 on the side of the suction box 2 which is adapted to have a pipe 20 from a suitable suction fan or other device connected thereto.

Upon the upper ends of the standards 22 are fixed the usual guide disks 32 for the roll of the film, the standard on the take-up side having the usual arbor 32' driven by a belt 33 from the roller shaft 25, this belt being preferably made from a coiled wire. Upon the standard 22 on the feed side of the machine is carried a cylindrical arbor 34, (Figs. 1 and 7) pressed by a spring 34' against the disk 32 thereby forming a slight frictional retardation to the rotation of the arbor. The roll of film is held upon this arbor by a rod 35 which projects down in front of the disk 32 from a head 35' having an integral pin 35^a supported in the upper end of the standard 22, a coiled spring 35^b being adapted to hold a V-projection 35^c on the head 35' in yielding engagement with a complementary notch in the adjacent face of the standard and so yieldingly hold the rod in position projecting across the face of the disk 32 while permitting it to be readily swung to one side when desired.

Formed in the punch head 11 is a chamber 11' (Figs. 2 and 12) in which are disposed a pair of blocks 36 and 36' which carry the punches 37 and the pilots 37' respectively, the pilots being somewhat longer than the punches so as to enter the previously made perforations in the film before the punches reach the latter, the ends of the pilots being tapered to accommodate and correct any slight inaccuracy in positioning of the film.

These blocks 36, 36' are secured in position by means of a bolt 38 passing through registering slots 38' in the blocks 36 and 36' and supported at opposite ends in cheek plates 11^a forming the side walls of the chamber 11'. Disposed in the chamber 11' and resting on the blocks 36 and 36' are plates 39 which are engaged on their upper sides by screws 39' which are threaded downwardly through the head 11 to provide for vertical adjustment of the punches and

pilots. The front wall of the chamber 11' may be formed by a removable face plate 11^b.

Carried upon the top of the casing 1 on opposite sides of the die 4 are film guiding and supporting devices which are in the main each of similar construction and arranged to prevent contact of the emulsified central portion of the upper surface of the film therewith. These film supporting and guiding devices comprise a pair of bed plates 40, 40' the former of which is on the entering or feed side of the machine and the latter on the discharge or take-up side. These plates are of substantially similar construction and provided with centre and side rows of film supporting rollers 41 which project slightly above the top surfaces of the plates. The plate 40' is fixedly secured on the casing 1 while the plate 40 is mounted to have transverse adjustment thereon so as to properly direct the film on to the die. To this end the plate 40 is fixed on a bracket 42 which is transversely slidable on the end of the casing 1 and has swiveled therein a screw 43 taking through a block 44 fixed to the end of the casing. A set screw 45 which passes through the end of the bracket 42 and is threaded into the block 44 serves to fix the bracket in adjusted positions.

Co-operating with the plates 40, 40' are upper guide members which are in the form of blocks 46, 46' slidable in frames 47 hinged at one side, as indicated generally at 48, to the casing 1. These blocks carry two rows of side rollers 49 in juxtaposition to the corresponding rows of rollers 41, these rollers 49 projecting slidably below the bottom faces of the blocks, the centre portions of which may be longitudinally grooved as at 50. The blocks 46, 46' are slidably suspended from the undersides of the frames 47, having fixed projections 51 which extend upwardly through the central openings of the frames and project freely over the sides of the latter. From these projections pins 52 extend outwardly, passing freely through the outer members of the frames, these pins being encircled by coiled expansion springs 53 which bear between the frames and the projections 51 and normally urge the blocks 46, 46' inwardly toward the die 4.

The purpose of this slidable mounting of the blocks 46, 46' is to permit of their being moved outwardly to clear the punch head 11 when it is desired to swing them away from the plates 40, 40' for insertion of the film or other purposes, and means are preferably provided to ensure of the blocks being moved outwardly to clear the punch head before being swung back. As here shown these blocks carry fixed pins 55 which engage under fixed hooked elements 56, clearing the same when moved outwardly, the projections 51 being adapted to engage behind retaining posts 57 when the frames 130

47 are swung back and so retain the blocks in their outer positions. Upon the entrance side of the machine are arranged a pair of 5 slideable guide bars 58, 58' which are located on opposite sides of the bed plate 40, the bar 58 being pressed by springs 59 toward the bar 58' this arrangement permitting the bar 58 to yield to accommodate itself to slight variations in the width of 10 the film.

The mechanism of the machine is all driven from a common main shaft which has already been referred to and which is illustrated in detail in Fig. 9, being of sectional construction arranged to permit of the ready removal of the stripping and shifting devices which are arranged as a single unit removably mounted in the casing 1. This shaft comprises a sleeve 60 having an integral eccentric 61 between its ends whereby it operates the ram 10 to which latter it is connected by means of a link 62 pivotally attached at its upper end to a pin 63 on the ram and having a strap 25 or collar 64 on its lower end which encloses the eccentric 61, an anti-friction bearing 65 being interposed between the eccentric and collar. This sleeve 60 extends through and is journaled in the offset 13' before referred 30 to, an anti-friction bearing 66 being provided at this point, a nut 67 being screwed upon a left hand screw threaded portion of the sleeve just outside the bearing 66, the sleeve terminating in a diminished portion 68 on 35 which is mounted a stepped pulley 69. This pulley is connected by a belt 70 with another stepped pulley 71 on the shaft of an electric motor 72 carried in a box 73 supported by the legs 3 under the suction box 2.

40 The forward end of the sleeve 60 engages, by means of transverse tongue and groove elements 60', the worm pinion 15 which latter is supported on a front shaft section 75 which has formed integral thereon 45 a series of cams for operating the stripper and shifter devices, the pinion 15 being connected to this shaft section 75 for rotation by transverse tongue and groove elements 75'. The sleeve 60, shaft section 75, 50 and pinion 15, are all locked together by means of a headed screw 75 which is entered from the rear end of the sleeve and is screwed into a tapped recess in the rear end of the section 75, the forward end of which 55 is journaled in a removable plate 77 closing an opening in the front of the casing 1 and carrying the shifter and stripper devices.

The shifter device advances the film step 60 by step over the die, and is located on the discharge side of the machine so as to engage the perforations just made by the die, and comprises a block 80 having two rows of 65 upwardly projecting pins 81 spaced properly to engage the perforations in the film.

This block is fixed on the upper end of a vertically movable slide 82 having a dovetail engagement, as shown in Fig. 4, with a horizontally movable slide 83 guided in a guide 84 fixed on the plate 77. The slide 70 83 receives horizontal motion from a cam 85 on the shaft section 75 which engages between a pair of vertically faced projection 86 and 87 on the face of the slide 83, the latter projection serving as a guide for 75 the slide 82. The slide 82 receives vertical motion from a second cam 88 on the shaft section 75 which engages a roller 89 mounted near one end of a rocker lever 90 fulcrumed at its opposite end as at 91 80 on a projection 92 from the plate 77. This lever is connected as at 93 to a block 94 85 slideable in a horizontal groove 95 in the slide 82. The cam 88 bears upwardly against the roller 89 and thus moves the 85 slide 82 upwardly, the latter being returned or moved downwardly by a coiled expansion spring 96 bearing between the two elements 97 and 98 of a compound or telescopic link pivotally connected at its upper end to the 90 free end of the lever 90 and at its lower end to the plate 77. As will be apparent from the foregoing the block 80 will have both a horizontal and a vertical movement imparted thereto, the cams 85 and 88 being 95 so arranged as to have the two movements occur in rotation. The pins 81, or claws as they are preferably designated, are accommodated in longitudinal slots 99 of the bed plate 40', the block 46 being also grooved 100 on its underside as at 100 to accommodate the upper ends of the claws which in their upper position project, as will be apparent, above the meeting points of the lower and upper sets of rollers 41 and 49. It will 105 also be understood of course that the parts will be so arranged as to have the claws 81 register exactly with the perforations which have just been made in the film.

The film is stripped from the punches and 110 pilots when the latter are raised, by means of a stripper comprising a plate 105 having perforations 106 corresponding in arrangement to those of the die 4, this plate having an integral extension 107 fixed on the upper 115 end of a slide-block 108 guided in a suitable recess 108' in the plate 77. The slide-block 108 is formed near its lower end with a projecting finger 109 which is engaged on its underside by a cam 110 on the shaft section 75, an expansion spring 111 which bears on the upper side of the finger 109 normally urging the stripper downward. Downward movement of the stripper is limited by means of an adjustment screw 112 120 which is threaded upwardly through the plate 77 into the recess 108', the screw 112 being preferably adjusted so as to prevent the weight of the stripper bearing down on the film. 125

- In the operation of the machine the unperforated roll of film is placed on the arbor 34, the film, which is indicated in dotted lines at X in Fig. 1 is suitably led 5 around the roller 28 and between the bed-plates 40, 40' and blocks 46, 46', passing over the die 4, the end of the film being passed upwardly through the suction cleaner 29, around the roller 27, to the arbor 32'. 10 Upon the motor being started and the main shaft operated the rollers 26 and 27 and arbor 32' will be rotated causing the film to be unwound from the arbor 34 and wound on the arbor 32'. As the punch head re- 15 ciprocates the punches 37 will perforate the film, the pilots 37' entering the previous perforations and accurately positioning the film. While the punch head is raising the cam 110 allows the stripper 105 to descend, 20 the claws 81 at the same time rising to engage in previously made perforations and when the punches and pilots have cleared the film the claws are moved horizontally the proper distance, bringing the last made 25 perforations under the pilots, the claws dropping down as the punch head descends.

As will be apparent in this improved perforator the operating mechanism is located below the path of travel of the film so that 30 danger of oil dropping on the latter is obviated. Also the operating mechanism is substantially all enclosed and out of the way while at the same time it is easily accessible, the stripper and shifting mechanism being 35 readily removed as a unit by loosening screw 76 and removing the bolts holding the plate 77 in place, the removal of this plate exposing the gears and shaft for operating the feed and take-up rollers 26 and 27. Also 40 the punchings from the film are carried away so that danger of these punchings catching on fire is eliminated.

What I claim is as follows:—

1. In a film perforator, a casing, a pair 45 of vertically slidable elements located respectively at the rear and front of the casing, the rear element having a forwardly projecting punch head formed on its upper end and the front element having a stripper member projecting rearwardly from the top thereof under the said punch head, film advancing means carried by the casing between the said slidable elements, and a shaft extending through said casing from front to 50 rear and operatively engaged with said slid- able elements and said film advancing means.

2. In a film perforator, a casing, a pair of vertically slidable elements located respectively at the rear and front of said casing, 60 a removable plate supporting the front element, a punch head and a stripper member carried respectively by the rear and front elements, a shaft formed in two sections operatively engaged with the said slide ele- 65 ments, one section of the shaft being mount-

ed in the said removable plate and the other section being mounted in the main body of the casing.

3. In a film perforator, a casing, a pair of vertically slidable elements located respectively at the rear and front of said casing, a removable plate supporting the front element, a punch head and a stripper member carried respectively by the rear and front elements, a shaft formed in two sections 70 operatively engaged with said slide elements, one section of the shaft being mounted in the said removable plate and the other section being mounted in the main body of the casing, and means connecting the two 75 sections of the shaft together adapted to engage and disengage by longitudinal movement of the two sections towards and away from one another.

4. In a film perforator, a vertically mov- 85 able slide block, a support therefor, a strip- per member carried by said slide block, a lateral projection from said slide block, a cam engaging said projection and adapted to raise said slide block, and a spring bear- 90 ing downwardly on said projection to cause the stripper member to engage with the film.

5. In a film perforator, a casing, a re- 95 movable plate on one side of said casing, a punch, film stripping and shifting devices mounted on said removable plate, a shaft for operating said punch and stripping and shifting devices, said shaft being formed in separable sections one of which is journaled in the said removable plate.

6. In a film perforator, a casing, a remov- 100 able plate on one side of said casing, a punch, film stripping and shifting devices mounted on said removable plate, a shaft for operating said punch and stripping and shifting devices, said shaft being formed in separable sections one of which is journaled in the said removable plate, the other sec- 105 tion being hollow, and a screw inserted through the hollow section and engaging the first mentioned section to hold the two shaft sections together.

7. In a film perforator, a punch, and means for intermittently advancing the film under the punch comprising a shaft, a pair 115 of cams on said shaft, a horizontally mov- able slide, a second slide adapted to move horizontally with the first slide and to have vertical movement independently thereof, and operative connections between the said 120 slides and the respective cams.

8. In a film perforator, a punch, and means for intermittently advancing the film under the punch comprising a shaft, a pair of cams on said shaft, a horizontally mov- 125 able slide, a second slide adapted to move horizontally with the first slide and to have vertical movement independently thereof, and operative connections between the said slides and the respective cams, the operative 130

connection between the first slide and its cam comprising a pair of vertically faced projections on said slide projecting on opposite sides of said cam.

- 5 9. In a film perforator, a punch, and means for intermittently advancing the film under the punch comprising a shaft, a pair of cams on said shaft, a horizontally movable slide, a second slide adapted to move 10 horizontally with the first slide and to have vertical movement independently thereof, and operative connections between the said slides and the respective cams, the operative connection between the second slide and its 15 cam including a rocker lever, and a block carried by said lever engaging in a horizontal groove in said slide.
10. In a film perforator, a casing, a punch, film advancing means comprising a sectional 20 shaft, a pair of cams on said shaft, a horizontally movable slide, a second slide adapted to move horizontally with the first slide and to have vertical movement independently thereof, means operatively connecting said slides and the respective cams, 25 and a removable plate forming a part of said casing upon which said film advancing means is mounted.
11. In a film perforator, a punch, a die, a 30 device for supporting and guiding the film while being fed to the die, a casing on which said device is mounted, and means for adjusting said device transversely to the path of movement of the film, comprising a 35 bracket to which said device is fixed, and an adjusting screw swiveled in said bracket and threaded through a fixed part on the said casing.
12. In a film perforator, a punch, a die, a 40 device for supporting and guiding the film while being fed to the die, said device including separate members adapted to engage the upper and lower surfaces of the film,
- and means hingedly mounting the upper members whereby they may be swung back 45 from operative position.
13. In a film perforator, a die, a punch, a punch head, separate film guiding members adapted to engage the upper and lower surfaces of the film, the upper members normally projecting under the said punch head, hinged frames in which said upper members are slidably mounted, and means locking said frames against swinging movement when the said upper members are in normal 55 position.
14. In a film perforator, a die, a punch, a punch head, separate film guiding members adapted to engage the upper and lower surfaces of the film, the upper members normally projecting under the said punch head, hinged frames in which said upper members are slidably mounted, and means locking said frames against swinging movement when the said upper members are in normal 60 position, said means being automatically releasable by sliding the said members in the said frames.
15. In a film perforator, a die, a punch, a punch head, separate film guiding members 70 adapted to engage the upper and lower surfaces of the film, hinged frames in which the upper members are normally mounted, springs urging the said upper members to position projecting under the said punch 75 head, hinged frames in which said upper members are slidably mounted, and means locking said frames against upward swinging movement until the said members have been drawn back to clear the said punch 80 head.

Signed at Brooklyn, city of New York, in the county of Kings and State of New York this 2nd day of July, A. D. 1920.

CHARLES R. CARLETON.
